UNITED STATES PATENT OFFICE.

WILLIAM H. NICHOLLS, OF BROOKLYN, NEW YORK.

MOLDING-MACHINE.

1,249,994.

Specification of Letters Patent. Patented Dec. 11, 1917.

Application filed January 7, 1911, Serial No. 601,420. Renewed March 14, 1916. Serial No. 64,238.

To all whom it may concern:

Be it known that I, WILLIAM H. NICHOLLS, a citizen of the United States, and a resident of Brooklyn, county of Kings, and State of New York, have invented certain new and useful Improvements in Molding-Machines, of which the following is a full, clear, and exact description.

This invention relates more particularly to machines in which the sand is squeezed or packed by mechanical means about a pattern held in a flask.

The primary object of the invention is to provide simple and efficient means by which the cope and drag members of a flask may be held upon a movable parting plate forming a means to support the two members of the flask and in which the sand may be manually or otherwise placed about the pattern within the flask members and the flask moved into position in alinement with suitable pressing devices and by suitable means pressure applied on opposite sides of the flask so as to pack the sand about the pattern; and to provide a pressing device which is so controlled that air pressure may be applied and the said pressing device positively moved toward and away from the flask and held in such a way that in its positive movement from the flask, it is so guided that it will not jar or affect either member of the flask or the supporting means therefor which would likely damage the mold as is often the case in machines of this character as ordinarily constructed in which the movable pressing device is positively moved in one direction only and permitted to move in the opposite direction by gravity.

Other objects of the invention are to provide simple and efficient means for supporting the flask members on opposite sides of a parting plate and for holding the same to said plate; to provide simple means whereby the cope member of the flask may be held to one of the pressing devices; to provide simple means whereby a normally stationary pressing device may be swung to one side to carry one of the flask members therewith, and to provide simple means whereby a piston carrying the movable

pressing device may be positively operated in one direction and by simple mechanism returned to its former position.

Another object of the invention is to provide simple and efficient mechanism which will permit the parting plate and support to be rotated, and during the rotation to have the packing board of the flask moved inward to initially pack or squeeze the sand of the drag member of the flask.

A further object of the invention is to provide simple means whereby after the pattern has been removed and in case a core has been placed in position within the drag the said drag may be moved by a pressing device into position to be united to the cope member of the flask and during the upward movement of the pressing device the pressure of air may be automatically cut off at the proper point, and by manually operated means the entire flask permitted to lower with one of the pressing devices in position to be removed from the machine.

With these and other objects in view, the invention will be hereinafter more particularly described with reference to the accompanying drawings, which form a part of this specification, and will then be pointed out in the claims at the end of the description.

In the drawings, Figure 1 is a front elevation of one form of machine embodying my invention.

Fig. 2 is a vertical section, partly in elevation, taken on the line II—II of Fig. 4.

Fig. 3 is a side view.

Fig. 4 is a plan view, showing the parts in position for packing or squeezing the sand.

Fig. 5 is a sectional view, partly in elevation, showing the means for rotatably supporting the parting plate and its frame.

Fig. 5a is a section of one form of valve or cock that may be used in connection with the pneumatic pressing means.

Fig. 6 is a plan view with the upper pressing device shown partly diagrammatic.

Fig. 7 is a fragmentary transverse section, partly in elevation, taken on the line VII—VII of Fig. 6, showing the pressing devices in the position shown in Fig. 6.

Fig. 7a is a sectional plan showing one

means for limiting the swinging movement of the upper pressing device, and the flask support.

Fig. 8 is a plan view showing how the 5 parting plate and the flask support are moved to one side out of the path of the pressing devices.

Fig. 9 is a detail plan view of one of the flasks.

10 Fig. 10 is a transverse section of the flask in position on the parting plate.

Fig. 11 is a transverse section showing the drag only on the pattern plate, the section being taken on the line XI—XI of 15 Fig. 8.

Fig. 12 is a view similar to Fig. 11 except that the pattern plate and supporting frame has been rotated one-half of a revolution to reverse the position of the drag 20 member of the flask.

Fig. 13 is a fragmentary plan view, partly in section and partly in elevation, showing how air under pressure is applied to the means for holding the cope of the flask to a 25 normally stationary pressing member of the machine.

Fig. 14 is a fragmentary section showing how the clamping fingers for the drag are automatically moved inward as the pattern plate and its support is rotated.

Fig. 15 is a section taken on the line XV—XV of Fig. 14.

Fig. 16 is an end view of Fig. 13.

Fig. 17 is a sectional view taken on the 35 line XVII—XVII of Fig. 16, showing one of the pneumatic devices for engaging the flask cope.

Fig. 18 shows partly in section and partly diagrammatic a transverse section of the 40 flask with the pressing devices in position to pack the sand about the pattern.

Fig. 19 is a fragmentary vertical section showing the flask member and parting plate after the mold has been made.

45 Fig. 20 is a sectional plan view showing another form of means for engaging the cope member of the flask to support the same.

Fig. 21 is a front view of Fig. 20.

50 Fig. 22 is a sectional view, partly in elevation, showing the means for adjusting the flask engaging devices, the section being taken on the line XXII—XXII of Fig. 20; and

55 Fig. 23 is a sectional view showing an adjustable screw which is adapted to determine the pressure which may be exerted by the upper normally stationary pressing device upon the cope.

60 The machine has a base 10 from which projects brackets or arms 11 and 12 and on the bracket 12 is a boss 13 in which is rigidly held a vertically-extending rod or post 14. This post is fixed in the boss 13 65 and has a collar 15 at the upper portion

thereof above which is pivotally held a frame arm 16, the said arm having a boss 17 which is held between the collar 15 and a washer 18 by means of a nut 19 secured to the end of the post 14. The arm 16 is of substantial thickness to withstand the pressure or strain thereon and at the end opposite the boss 17 is a rod 20. This rod 20 has a threaded end and is held to the arm 16 by means of a nut 21 secured to said rod and a washer 22 and nut 23 on the end 70 of said rod. The lower end of the rod 20 is provided with collars 24 and 25 and the said collars are so spaced as to engage opposite faces of the enlarged part 26 formed 75 on the end of the frame bracket 11. The boss 26 is slotted on one side, as at 27, so that when the frame arm 16 is swung on its pivot into substantial alignment with the brackets 11 and 12, the said rod will enter 80 the recess 27 and by means of the collars 24 and 25 be detachably held thereto. The arm 16 with its post 14 and brackets 11 and 12 and base 10 form a substantial frame for the parts of the machine and permits the 85 frame arm 16 to be moved on its pivot for purposes to be presently described.

A flask frame and supporting means 28 is pivotally held to the post or upright 14, Fig. 8, and this frame has a supporting arm 29 provided with a boss 30 which is pivotally held to the post 14 between the fixed collars 31 and 32. The arm 29 has a rod 33 held to the outer end thereof and on the other end of said rod opposite the arm 29 and substantially parallel therewith is an arm 34. One end of the arm 34, as 35, is secured to the rod 33, and the other end of said arm is slotted, as at 36, and is adapted to span the rod 20 105 when the flask frame and supporting means is swung over the base and the brackets 11 and 12 as shown in Figs. 1 to 4, there being two collars 36^a to support and hold the arm 34. The frame 28 is located substantially intermediate the frame arm 16 and the frame brackets 11 and 12, and held to the rod 33 are the arms 37 and 38. These 110 arms are each similarly constructed and at their outer ends are bifurcated to provide 115 overhanging opposed lips or bosses 39 and 40 (Fig. 2). A vertical rod 41 is held between the bosses 39 and 40 and held to slide on each rod 41 is a bearing 42. A parting or pattern plate 43 is held to a frame 44 which is substantially rectangular in form and on opposite sides of the plate the cope 45 and the drag 46 of the flask is adapted 120 to be held, as shown best in Figs. 1 and 2. This parting plate and frame has a stud 47 projecting outward therefrom on opposite sides forming trunnions for the parting plate frame and said studs 47 are journaled in the bearings 42 so that said parting frame may be rotated.

The flask parting plate and its frame may be swung outward to the position shown in Fig. 8, and the drag member of the flask is placed thereon over one-half of the pattern held to the pattern plate as usual. The drag is filled with sand in any desired manner and over the sand is placed a flask packing board 48 which may be strengthened by transversely extending wooden strips 49, and when the said drag is filled with sand the packing board which fits loosely in the frame of the flask drag is held upon the surface of the sand by means of fingers 50. These fingers 50 one at each end of the pattern plate frame, are held to the rods 51 and are adapted to be manually swung over the drag so as to engage the outer surface of the flask packing board 48 in order that the parting plate frame may be swung on its pivots to invert the drag member of the flask. The rods 51 to which the fingers are secured are slidably held in a boss 52 of the parting plate frame and carried by each rod is a bracket or block 53. This block has a substantially rectangular opening 54 which is engaged by an eccentric disk 55 formed as a part of each bearing 42, so that when the parting plate frame is rotated the eccentric 55 on each side thereof around the pivot studs 47 will cause a relative movement to be given to the blocks 53 which will automatically force the fingers inward and in doing so will force the board 48 also inward to initially pack the sand and to hold the sand within the drag of the flask. The parting plate frame has lugs 55^a which are adapted to engage pins or projections 56 to cause the frame to readily assume a horizontal position, the said frame being first rotated in one direction and then in the other to reverse the position of the parting plate frame.

The drag member of the flask is provided with lugs, as 56^a, on opposite sides thereof from which extend pins 57, Figs. 11 and 12, and these pins pass through openings in the parting plate, and on the frame of the cope member 45 are lugs 58 having openings therein adapted to receive the pins 57, to properly align the cope and drag. The pattern, if comprising two parts may be placed and held on the opposite sides of the parting plate 43 and the cope frame may be filled with sand in the usual or in any preferred way, and a flask packing board 59 placed over the sand, the said board being provided with strengthening bars or strips 60. In this condition with the flask members held to the parting plate 43, the frame 28 with the flask is then swung inward carrying the flask therewith and until the arm 34 engages the vertical rod 20 between the collars 36^a so as to be aligned directly over the frame bracket arms 11 and 12 and under the frame arm 16, the horizontal swinging movement

of the frame 28 and parting plate being limited in both directions by a pin or projection 60^a, Fig. 3, which is adapted to engage either of the lugs 60^b on the boss 30 of the arm 29.

To press the mold from one side, I provide a normally stationary pressing device, platen or head 61. This device is substantially rectangular in form and said head is rigidly secured to a flange 62 from which projects a threaded rod or stem 63. This threaded rod or stem 63 engages a threaded opening in the frame arm 16 and by rotating the stem 63 manually by means of the device 61 the pressing surface of said device may be properly positioned with respect to the cope member of the flask, the said device 61 remaining fixed after being once set. The pressing device 61 may be swung to one side for access to either or both flask members and said movement may be limited in either direction by a pin 62^a carried by the boss 17 of the arm 16, which is adapted to engage either of the lugs 62^b on the collar 15.

A movable pressing device 64 is located directly in line with the normally fixed head 61 and this pressing device is secured by bolts 65 to a vertically movable piston 66 held to move in a cylinder 67 forming a part of the machine base 10. The pressing part 95 of the device 64 may be cut lengthwise thereof, as at 68, as said device engages only the strengthening bars 49 and 60 of the flask packing boards 48 and 59. The piston 66 is provided with packing rings 69 so that it may fit tightly within the cylinder 67 and provide a substantial support for the pressing device 64, and within the piston 66 is a smaller cylinder 70. The piston 66 is closed at its lower end and open at the upper end thereof and the cylinder 70 is also open at the upper end thereof. A piston 71 is held to a fixed rod 72 by a nut 73 at the upper end thereof, and said rod is held by a nut 74 to a flange 75 forming a part of the cylinder head 76, which latter may be formed integral with the base 10. The piston 66 is provided with an opening 77 in which extends a rod 78 which is held at its lower end by a nut 79 to the cylinder head, and said rod 78 serves to prevent rotary movement of the piston and the pressing device 64. This rod 78 may be grooved lengthwise, as at 80, to prevent air from accumulating within the recess or chamber 77, and said rod 78 as well as the fixed piston rod 72 may pass through packing glands, if so desired, to prevent leakage past the same during the upward movement of the piston 66.

A pipe 81 leads to a source of air supply under pressure and in this pipe is a three-way valve 82. This valve connects with a pressure pipe at 83, with an exhaust at 84 (Fig. 1), and with the head of the cylinder 66 by a pipe 85, the valve or plug 86 being

provided with a passage 87 which by a partial rotation may be made to form a communication between the pressure supply and the pipe 85 for the pressure cylinder, or the 5 said passage may form a communication with the pipe 85 and the pipe 84 in order that the pressure within the cylinder may be exhausted. The pressure pipe 81 has a separate and independent connection 88 10 with a passage 89 extending upwardly through the rod 72 to the upper portion thereof and under the piston 71, so that the full pressure of air may pass into the cylinder 70 under the piston 71. It will be seen 15 that when the pressure of air is admitted under the main piston 66 and the full pressure permitted to flow through the passage 89 into the cylinder 70 the relatively different diameters between the cylinder 70 and 20 the pressure surface of the piston 66 is such that piston 66 and the pressing device 64 carried thereby will be forced upwardly. This will exert pressure against the flask packing board 48 and the entire flask will 25 be elevated along the rods 41 carried by the frame 28 of the flask-supporting means, until the packing board 59 of the cope member engages the under surface of the pressing device 61 the pressure being such that 30 the packing boards will be pressed inward to properly pack the sand about the pattern. At the time that the pressing device 64 and the piston 66 is forced upward the air within the cylinder 70 will be forced outward to 35 the source of supply or tank containing the same through the passageway 82 and as soon as the valve 82 is turned to form a communication between the exhaust and the pipe 85 the pressure within the cylinder 40 70 acting on the piston 71 and the head of the cylinder 70 will force the same downward again to its normal position. By this means the piston 66 may be made to fit tight against all vibration within the cylinder 45 67 so that the pressing device 64 will be positively moved both up and down without tending to shake or jar the flask member or members which may be supported thereon or engaged thereby. This overcomes all liability to jar or break the mold during the 50 lowering of the device 64 as might result if the piston 66 fits loosely enough within the cylinder to allow the cylinder and device 64 even with the flask or member thereon on 55 said device to return to its normal position by gravity.

The cope member of the flask after the sand has been properly packed or squeezed about the pattern and before the piston 66 is 60 lowered should be held so as to be supported on the pressing device 61. To secure this various means may be employed. As one means I form the device with an upwardly projecting wall 90 extending along the sides 65 and ends of the device 61, and arranged at the ends of said device and on the wall 90, are guides 91. There are two guides one at each end of the device 61, and the reason for arranging the guides only at the ends is that the flasks usually vary less in their 70 width than in their length, and on this account I provide adjustable means for engaging and holding the flask cope at the sides thereof. Two brackets 92 are held to the guides 91 and engaging a threaded opening in a boss on each bracket is the threaded end of a bolt 93. This bolt 93 is supported in a lug 94 projecting from the wall of the device 61 and has polygonal parts 95 by which the said bolt may be rotated, and carried by each bracket is a screw 93^a the lower end of which is adapted to engage the upper edge of the cope frame during the squeezing of the sand by the pressing devices 61 and 64, the purpose of the screws being to 80 limit the extent of inward movement of the cope packing or squeezing board 59 and consequently the extent of compression in said cope. One end of the bolt 93 has left-handed threads and the other end right-handed threads so that by the rotation of the bolt 93 the brackets 92 may be moved toward or from each other to adjust the same along the guide 91 at each end of the device 61 according to the width of the flask. A 85 cylinder 96 is angularly arranged on each bracket 92 and each cylinder has a piston 97 therein to which is held a rod 98, the lower end of which is tapered and is adapted to engage under the lugs 100 formed on the 90 side walls of the cope frame, a spring 97^a being arranged in each cylinder to force the piston in one direction. These lugs 100 (Fig. 1) are tapered to adapt the tapering ends 99 of the rods to engage under the same 100 and owing to the angular position of the rods, the cope will be held against vertical movement when the said ends 99 engage the lugs 100. Each cylinder is provided with a cylinder head 101 and these heads are connected by a pipe 102 to a passage 103 in the flange 62, and this passage communicates with a vertical passage 104 through the threaded stem 63. The passage 104 is connected by a pipe 105 which is held to the 110 threaded stem 62 by a packing box 106 and gland 107, and said pipe 105 is connected by a flexible or other pipe 108 to a pipe 109 leading to the source of supply pipe 81, a valve 110 similar to valve 82 being provided between the pipes 108 and 109 and controlled by a hand lever 111 whereby the pressure to the cylinders 96 may be cut off and exhausted or turned on at will. 115

The invention thus far described will be 120 readily understood from the foregoing description when taken in connection with the accompanying drawings. The cope and drag of the flask being arranged on the parting plate 43 and positioned between the press- 125 130

ing devices 61 and 64 as shown in Figs. 1 to 4, pressure is applied to pack the sand about the pattern as previously described. The air pressure is then turned on so as to cause the tapered ends 99 of the piston rods 98 movable in the cylinder 96 to engage under the lugs 100 which will hold the cope member of the flask to the normally fixed pressing device 61. The valve 82 through the lever 112 is then operated to form a communication between the pipe 85 and the exhaust 84, and as soon as this occurs the air passing through the pipe 88 into cylinder 70 will lower the movable pressing device 64. Before this is done the fingers 50 are moved away from the drag so that said drag will lower with the device 64. The parting plate with its frame will also lower at this time on the rods 41 until arrested by the lips or bosses 40 of the arms 37 and 38, leaving the cope held to the pressing device 61. The pressing device 64 with the drag continues to lower away from the parting plate when the mold will be complete. The parting 25 plate and the supporting frame 28 may be moved outward and a core, if used, may be placed in the drag and the two members of the flask again brought together by air pressure on the piston 66. At this time the 30 pressure in the cylinders 96 for the cope supporting devices may be released which will permit the cope to lower with the drag when the piston 66 and device 64 may be lowered in the manner already described and the flask then removed from the machine.

The stem of the plug of the three-way valve or cock 82 has a hand lever 112 secured thereto by which the said valve may be rotated to permit air under pressure to 40 pass to the cylinder 67, and this lever has an arm 113 connected to an arm 114 which is pivoted at 115 to the base 10. A bar 116 is carried by the pressing device 64 to move upward therewith and said bar is slotted, as at 45 117, into which slot extends a projection, as 118, from the arm 114. The lower end of the bar 116 is provided with an adjustable screw 119 whereby when the device is moved upward the screw may be made to operate 50 the arm 114 and owing to its connection with the valve operating lever 112 will automatically throw the same to the position shown in dotted lines at 120 (Fig. 3) which will determine the extent of upward movement 55 of the piston 66 and device 64 and automatically prevent the pressure from becoming too great. When the piston is to be lowered all that is necessary to do is to shift the lever from the position shown in dotted lines at 60 120 to the position shown in dotted lines at 121 which will form a communication between the cylinder and the exhaust to permit the piston to be forced downward by the pressure within the cylinder 70 as already described. It will be understood, however,

that the lever 112 may be operated entirely by hand or automatically in the manner described as preferred.

In Figs. 20 to 23 a different form of means is provided for engaging and holding the cope of the flask to the pressing device 61. Here the pressing device 61 is constructed substantially the same as that already described having guides 122 similar to the guides 91, and on these guides are adjustably held brackets 123. These brackets are adjusted toward and from each other by means of bolts 124 one end of which is provided with right-handed threads and the other with left-handed threads so as to move both brackets 123 inward or outward according to the direction of movement of the said bolt 124. Each bracket 123 carries a cylinder 125, and in the cylinder 125 is a piston 126 which is forced in one direction by a spring 127 the said spring being seated against one end of the cylinder and in a recess in the piston. A substantially L-shaped bar 129 is held at one end to the piston 126 and said bar 129 extends through a packing gland 130 in the cylinder head 131 and moves with the piston 126. A bolt 132 is adjustable in the lower end of the bar or bracket 129 and this bolt is held to said bar by a nut 133. The inner end of the bolt 132 is tapered at 134 and is adapted to engage an opening or recess 135 which may be readily formed in the side of the flask and particularly those flasks which do not have the lugs 100 shown in the other views. The cylinders 126 each communicate through a pipe 135^a to the source of pressure supply and it will be seen that when air under pressure is permitted to enter the cylinders 126 in a manner similar to that already described, the piston will be forced inward and in doing so will force the tapered end 134 into the recess 135 of the cope frame and will support the same above the parting plate, the upper edge of the frame being adapted to be engaged by the ends of adjustable bolts 136 which limit the upward movement of the cope and consequently the pressure exerted by the device 61.

It will be seen under the construction 115 shown that during the up and down movement of the pressing device 64 the sand will be properly packed or squeezed about the pattern held to the pattern plate, and as soon as the cope is held to the pressing device 61, the lowering movement of the pressing device 64 will cause the pattern and its supporting plate to lower from the cope, and on further downward movement of the pressing device 64 the drag will be removed 120 from the pattern, thus entirely completing 125 the mold during one complete movement of said pressing device 64. It will also be seen by the means shown the pressure on the cope and drag will vary so that the sand 130

will be squeezed or packed to a greater extent in the drag than in the cope, which is desirable. This is accomplished by adjusting the screws 93^a to adapt the same to engage the upper edge of the frame of the cope before the upward movement of the pressing device 64 has been completed. As the pattern and parting plate divides the two members of the flask, that is the drag from the cope, it will be seen that any movement of the pressing device 64 after the ends of the screws 93^a have engaged the frame of the cope will give additional pressure to the sand in the drag member of the flask as the cope is held at this time against movement and consequently from any pressing effect of the device 61. The device 64 will therefore squeeze or compress the sand in the drag to a greater extent than takes place in the cope according to the additional movement given said device 64.

While I have not described a device in the way of a vibratory hammer to strike the parting plate or other part to assist in the separation of the flask members, it will be understood that such a device or other means may be used; and it will be further understood that the form of supporting frame for the parting plate as well as other features may be varied and that the flask members may have the sand supplied thereto by a hopper or by any other suitable means.

From the foregoing, it will be seen that simple and efficient means is provided whereby the pressing device operating upon the drag of the flask may be positively driven both upward and downward, and the said device so supported that it will have an even and uniform movement so that it is not necessary for the movable pressing device to be returned by gravity; that simple and efficient means is provided whereby the cope of the flask may be supported above the parting plate; that simple means is provided for supporting the parting plate so that it may be moved to one side of the machine; that simple means is provided whereby the packing board of the drag may be positively held and the said holding means automatically actuated to initially press the board against the sand in the drag; that simple means is provided whereby the flask may be held and supported between the means for exerting pressure; and that simple means is provided whereby the pressure of air may be automatically cut off or manually, as preferred.

Having thus described my invention, I claim as new and desire to secure by Letters Patent.

1. In a molding machine, the combination of relatively movable pressing devices, a rotatable and vertically movable parting plate adapted to support the drag and cope mem-

be of a flask on opposite sides thereof to move therewith, and means for simultaneously squeezing the sand in both flask members and then in one only and during the same relative movement of the pressing devices.

2. In a molding machine, the combination of relatively movable pressing devices, a parting and pattern plate having a limited vertical movement between said devices, means whereby the parting plate may support the flask members and be moved horizontally away from and between said pressing devices, and means whereby the sand may be simultaneously squeezed in both flasks and then in one only.

3. In a molding machine, the combination of relatively movable pressing devices, and a parting and pattern plate having a limited vertical movement between said devices, means whereby the parting plate may support the flask members and be moved horizontally away from and between said pressing devices, and means whereby the sand in the flask members may be squeezed to different extents.

4. In a molding machine, the combination of relatively movable pressing devices, a pattern plate horizontally movable to and from said pressing devices, means for supporting the drag and cope members of the flask on opposite sides of said plate, means whereby the pattern plate may have a limited vertical movement, means carried by one of the pressing devices adapted to limit the upward movement of the pattern plate by engagement with the cope frame, means for supporting the cope member by the pressing device, and means for operating one of the pressing devices to have a movement greater than the vertical movement of the pattern plate and cope whereby the pressure on the sand in the drag member of the flask may be greater than the pressure in the cope member.

5. In a molding machine, the combination of relatively movable pressing devices, a pattern plate horizontally movable to and from said pressing devices, means for supporting the drag and cope members of the flask on opposite sides of said plate, means carried by one of the pressing devices adapted to limit the upward movement of the pattern plate by engagement with the cope frame, means for supporting the cope member by the pressing device, and means for operating one of the pressing devices to press the sand in the drag member of the flask to a greater extent than in the cope member.

6. In a molding machine, the combination of relatively movable pressing devices, a rotatable pattern plate horizontally movable to and from said pressing devices, means for supporting the drag and cope members of

- the flask on opposite sides of said plate, means whereby the pattern plate may have a limited vertical movement, bolts carried by one of the pressing devices adapted to 5 limit the upward movement of the pattern plate by engagement with the cope frame, means for supporting the cope member by the pressing device, and means for operating one of the pressing devices to have a movement greater than the vertical movement of 10 the pattern plate and cope whereby the pressure on the sand in the drag member of the flask may be greater than the pressure in the cope member.
7. In a molding machine, the combination of relatively movable pressing devices, a pattern plate horizontally movable to and from said pressing devices, means for supporting the drag and cope members of the 15 flask on opposite sides of said plate, means whereby the pattern plate may have a limited vertical movement, and bolts carried by one of the pressing devices adapted to limit the upward movement of the pattern plate 20 by engagement with the cope frame.
8. In a molding machine, the combination of relatively movable pressing devices, a rotatable pattern plate horizontally movable to and from said pressing devices, means for supporting the drag and cope members of the 25 flask on opposite sides of said plate, means whereby the pattern plate may have a limited vertical movement, means carried by one of the pressing devices adapted to 30 limit the upward movement of the pattern plate by engagement with the cope frame, and means for operating one of the pressing devices to have a movement greater than the vertical movement of the pattern plate and 35 cope whereby the pressure on the sand in the drag member of the flask may be greater than the pressure in the cope member.
9. In a molding machine, the combination of relatively movable pressing devices, a 40 vertically movable pattern plate adapted to support the drag and cope members of a flask on opposite sides thereof and moving normally between said pressing devices, means for moving one of the pressing devices to compress the sand in the flask members, means located on one of the pressing 45 devices adapted to support the cope member, and means whereby the drag member may be released from the pattern plate and 50 supported by the pressing device during its downward movement and during such movement cause the pattern plate to be separated from the cope thereby completing the mold during one complete movement of said movable pressing devices.
10. In a molding machine, the combination of relatively movable pressing devices, a vertically movable pattern plate adapted to support the drag and cope members of a 55 flask on opposite sides thereof and moving 60
- normally between said pressing devices, means for moving one of the pressing devices to compress the sand in the flask members, and means whereby the drag member may be released from the pattern plate and 65 supported by the movable pressing device during the downward movement of said pressing device and during such movement cause the pattern plate to be separated from the cope. 70
11. In a molding machine, the combination of two pressing devices, a pattern plate supported between the pressing devices and having means to support flask members on opposite sides thereof, a cylinder, a piston 75 movable within said cylinder and having a relatively small cylinder within said piston, a normally stationary piston adapted to work within the cylinder of the large piston and having a tubular rod connected therewith, means for preventing the large piston from rotating and for guiding the same, means connecting the two cylinders to the same source of fluid pressure supply whereby, owing to the greater diameter of 80 the larger cylinder, the fluid actuating means within the smaller cylinder will be forced therefrom and still be under the same pressure as that in the larger cylinder, and means for exhausting the means for operating the large piston from the large cylinder and thereby permit the pressure in the small cylinder to move the pressing device in a downward or opposite direction to adapt the drag member of the flask to be 85 positively moved therewith without jarring. 90
12. In a molding machine, the combination of two pressing devices one of which is movable, means for supporting the cope and drag members of a flask between said devices, a cylinder, a piston movable within said cylinder and having a relatively small cylinder within said piston, a normally stationary piston adapted to work within the cylinder of the large piston and having a 95 tubular rod connected therewith, means connecting the two cylinders to the same source of fluid pressure supply whereby, owing to the greater diameter of the larger cylinder, the fluid actuating means within the smaller cylinder will be forced therefrom and still be under the same pressure as that in the larger cylinder, and means for exhausting the means for operating the large piston from the large cylinder and thereby permit the pressure in the small cylinder to move the pressing device in a downward or opposite direction to adapt the drag member of the flask to be moved therewith without 100 jarring. 105
13. In a molding machine, the combination of a normally fixed pressing device, a movable pressing device, means for supporting flask members between the pressing devices to adapt sand to be compressed, 110
- 125
- 130

means for forcing the movable pressing device toward the other pressing device, and automatic actuating means for controlling the extent of movement of said movable device.

14. In a molding machine, the combination of a normally fixed pressing device, a movable pressing device, means for supporting flask members between the pressing devices to adapt said to be compressed, a lever; a valve operated by said lever, pneumatically actuated means controlled by said valve for forcing one pressing device toward the other pressing device, and means controlled by the movement of said pressing device to actuate the lever and valve.

15. In a molding machine, the combination with a base having frame brackets projecting outward therefrom, of a vertically arranged post secured to one of the brackets, the other frame bracket having a slotted end, a frame arm pivotally held to the post, a rod held to the frame arm at one end and adapted to engage the slotted end of the frame bracket, and pressing devices one of which is mounted on the frame arm and the other on the frame base.

16. In a molding machine, the combination with a supporting frame, of a pressing device, a second pressing device, a piston to which said latter device is held, a cylinder in which said piston is movable, a cylinder forming a part of said piston, a relatively small piston arranged within the inner cylinder and having a diameter smaller than the diameter of the first-mentioned piston, and means for supplying air under pressure to the inner and outer cylinders from the same source of supply for the purpose set forth.

17. In a molding machine, the combination with a supporting frame, of a pressing device, horizontally movable means for supporting a flask, a second pressing device, a piston to which said latter device is held, a cylinder in which said piston is movable, a cylinder forming a part of said piston, a relatively small stationary piston arranged within the inner cylinder and having a diameter smaller than the diameter of the first-mentioned piston, and means for supplying air under pressure to the inner and outer cylinders from the same source of supply.

18. In a molding machine, the combination with a supporting frame, of a pressing device, means for supporting a flask, a second pressing device, a cylinder, and a piston movable with said second device and having pressure surfaces of relatively different areas, and means whereby air under the same pressure may be caused to act on said surfaces to force the piston toward and from the first-mentioned pressing device.

19. In a molding machine, the combination with a frame, of a normally stationary

pressing device, a pivotally held and swinging flask-supporting means, a second pressing device located beneath the first-mentioned pressing device, a piston movable with said second pressing device, means whereby air under pressure from the same source may be simultaneously exerted on the piston in opposite directions while the air acting on the piston to move it in one direction may be exhausted to permit the air to force the piston in the opposite direction.

20. In a molding machine, the combination with a frame, of a pressing device, flask-supporting means, a second pressing device, a piston movable with said second pressing device, and means whereby air under pressure from the same source may be simultaneously exerted on the piston in opposite directions.

21. In a molding machine, the combination with a frame, of a pressing device, flask-supporting means, a second pressing device located beneath the first-mentioned pressing device, a piston movable with said second pressing device, means whereby air under pressure from the same source may be simultaneously exerted on the piston in opposite directions while the piston is moved in one direction, and means whereby the air acting on the piston to move it in one direction may be exhausted to permit the air to force the piston in the opposite direction.

22. The combination with a support, of a normally fixed pressing device, a movable pressing device, means for movably supporting a flask between said devices, a piston movable with one of said pressing devices, a normally fixed piston held within the first-mentioned piston and having a tubular rod to admit air under pressure on one side of said piston, means for admitting air on one side of the larger piston and for controlling the air thereto, and a fixed guide rod entering a recess in said larger piston and adapted to form a guide therefor.

23. The combination with a support, of a pressing device, a second pressing device, means for supporting a flask between said devices, a piston movable with one of said pressing devices, a normally fixed piston held within the first-mentioned piston and having a tubular rod to admit air under pressure on one side of said piston, and means for admitting air on one side of the larger piston and for controlling the air thereto.

24. The combination with a support, of a pressing device, a movable pressing device, means for supporting a flask between said devices, a piston movable with one of said pressing devices, a normally fixed piston held within the first-mentioned piston and having a tubular rod to admit air under pressure on one side of said piston, means for admitting air on one side of the larger

piston and for controlling the air thereto, and a fixed grooved guide rod entering a recess in said larger piston and adapted to form a guide therefor.

5 25. In a molding machine, the combination with a frame, of a pressing device, means for moving said pressing device, means for supporting a flask above said pressing device, a second pressing device, a 10 threaded stem carried by said second pressing device whereby the latter may be manually adjusted, and bolts mounted on said pressing device adapted to engage a part of the frame of a flask to determine the pressing effect of the second pressing device. 75

10 26. In a molding machine, the combination with a frame, of a pressing device, means for moving said pressing device, means for supporting a flask above said 15 pressing device, a second pressing device, and a bolt mounted on said latter pressing device adapted to engage a part of the frame of a flask to determine the pressing effect of said device. 80

20 27. A molding machine, comprising a frame having one member pivotally held to the other, a normally fixed pressing device carried by the pivoted member of the frame, means for adjusting said device, a movable 85 pressing device, means for supporting a flask between the pressing devices, movable flask engaging devices mounted on the normally fixed pressing device, means to force said flask engaging devices into engagement with the flask, a piston to which the movable pressing device is held, and means 90 for positively forcing the piston and the movable pressing device into position to exert pressure and in a direction opposite 95

40 therefrom. 100

25 28. A molding machine, comprising a frame, a normally fixed pressing device, means for adjusting said device, movable flask engaging devices mounted on the normally 105 fixed pressing device, means to force said flask engaging devices into engagement with the flask, a movable pressing device, horizontally movable and pivotally held means for supporting a flask between the 110

50 pressing devices, and a movable piston to which the movable pressing device is held. 115

29. A molding machine comprising a frame, a normally fixed pressing device, means for adjusting said device, a plurality 120 of cylinders located on the normally fixed pressing device, movable flask engaging devices for the cylinders, means to force the flask engaging devices into engagement with the flask, a movable pressing device 125 and horizontally movable and pivotally held means for supporting a flask between the pressing devices, and a movable piston to which the movable pressing device is held. 130

30. A molding machine comprising a frame, a normally fixed pressing device, 135

means for adjusting said device, a plurality of cylinders located on the normally fixed pressing device, movable flask engaging devices for the cylinders, pneumatic actuating means to force the flask engaging devices into engagement with the flask, a movable pressing device, horizontally movable and pivotally held means for supporting a flask between the pressing devices and a movable piston to which the movable pressing device is held. 75

31. The combination with a frame, of a pressing device adjustably supported on said frame, a movable pressing device, pneumatically actuated means for forcing said second pressing device in opposite directions, a horizontally movable supporting means for a flask adapted to be moved between said devices, a plurality of adjustable 80

20 brackets carried by the normally fixed pressing device, a cylinder carried by each bracket, a movable flask engaging device for each cylinder, pistons to actuate said devices, and means for supplying air under pressure to said cylinders to force the devices into engagement with the flask. 85

25 32. The combination with a frame, of pressing devices, a plurality of cylinders, movable flask engaging devices for the cylinders, and means to force the devices into engagement with the flask. 90

33. The combination with a frame, of normally fixed and movable pressing devices, of a plurality of cylinders located on the normally fixed pressing device, movable flask engaging devices for the cylinders, and pneumatic actuating means to force the devices into engagement with the flask. 95

34. The combination with a frame, of a pressing device supported on said frame, a movable pressing device, a movable supporting means for a flask adapted to be moved between said devices, a plurality of cylinders, movable flask engaging devices one for each cylinder, pistons to actuate said devices, and means for supplying air under pressure to said cylinders to force the devices into engagement with the flask. 100

35. In a molding machine, the combination with a support, of a pressing device, a second pressing device, a plurality of cylinders, a piston movable in each cylinder, a spring normally forcing each piston in one direction, and means movable with the piston adapted to engage a part of a flask. 105

36. In a molding machine, the combination with a support, of a pressing device, a second pressing device, a plurality of angularly disposed cylinders, a piston movable in each cylinder, and means movable with each piston adapted to engage a part of the flask. 110

37. In a molding machine, the combination with a support, of a pressing device, a second pressing device, a plurality of angu- 115

larly disposed cylinders, a piston movable in each cylinder, a spring normally forcing each piston in one direction, and means movable with the piston adapted to engage 5 a part of the flask.

38. The combination with a supporting frame, of a normally fixed pressing device, a horizontally movable frame, a parting plate, a second pressing device, means for moving said second pressing device, guides arranged on the normally fixed pressing device, brackets adjustable along said guides, a bolt having oppositely threaded ends engaging the brackets to adjust them to and from each other, angularly arranged cylinders, a piston movable in each cylinder, a piston rod having tapered ends movable with said piston and projecting outward from the cylinder and adapted to engage lugs on a flask frame, and means for supplying air under pressure to the cylinders.

39. The combination with a supporting frame, of a pressing device, a horizontally movable frame, a parting plate carried by 25 said frame, a second pressing device, means for moving said second pressing device, guides arranged on the normally fixed pressing device, brackets adjustable along said guides, a bolt having oppositely threaded 30 ends engaging the brackets to adjust them to and from each other, a plurality of cylinders, a piston movable in each cylinder, and a piston rod movable with each piston and projecting outward from the cylinder and 35 adapted to engage the flask frame.

40. The combination with a supporting frame, of a normally fixed pressing device, a movable frame, a parting plate, a second pressing device, means for moving said second pressing device, guides on the normally fixed pressing device, a plurality of cylinders, a piston movable in each cylinder, a piston rod movable with each piston and projecting outward from the cylinder and 45 adapted to engage the flask frame, and means for supplying air under pressure to the cylinders.

41. The combination with a main frame having a vertical post, of two relatively 50 movable pressing devices carried by the frame, a pivotally held frame arranged intermediate the pressing devices and comprising an arm pivotally held to the post, a rod and a second arm substantially parallel 55 to the first-mentioned arm and adapted when in one position to engage a part of the main frame, and means carried by the rod to support a flask.

42. The combination with a main frame 60 having a vertical post, of two relatively movable pressing devices carried by the frame, a pivotally held frame arranged intermediate the pressing devices and comprising an arm pivotally held to the post, 65 a rod and a second arm substantially parallel

to the first-mentioned arm and adapted when in one position to engage a part of the main frame, and a rotatable parting plate carried by the rod to support a flask.

43. The combination with a main frame 70 having a post, of two relatively movable pressing devices carried by the frame, a pivotally held frame arranged intermediate the pressing devices and comprising an arm pivotally held to the post, and a rod, and 75 a rotatable parting plate carried by the rod.

44. The combination with a frame, of two relatively movable pressing devices supported by said frame, said frame having a vertically extending post, a parting plate, 80 a frame for said plate, bearings for rotatably supporting said parting plate frame, arms to which the bearings are slidably held to permit vertical movement of the parting plate frame and plate, clamping 85 fingers adapted to engage one of the flask boards, rods to which said fingers are held, means whereby lengthwise movement may be given to the rods to cause the fingers to press upon the flask board, together with 90 means for pivotally mounting the arms upon the vertical post to permit the parting plate frame to be moved between the pressing devices or away therefrom.

45. The combination with a frame, of two relatively movable pressing devices supported by said frame, a parting plate, a frame for said plate, bearings for rotatably supporting said parting plate frame, arms to which the bearings are slidably held to 100 permit vertical movement of the parting plate frame, clamping fingers adapted to engage one of the flask pressing boards, and means for moving said fingers.

46. The combination with a frame, of relatively movable pressing devices supported by said frame, a parting plate, a frame for said plate, bearings for rotatably supporting said parting plate frame, arms to which the bearings are slidably held to permit vertical movement of the parting plate frame, clamping fingers adapted to engage one of the flask pressing boards, rods to which said fingers are held, eccentric means whereby lengthwise movement may be given 115 to the rods to cause the fingers to press upon the flask presser board, together with means for pivotally mounting the arms upon the vertical post to permit the frame to be moved between the pressing devices or away 120 therefrom.

47. The combination with a frame of two relatively movable pressure devices supported by said frame, said frame having a vertically extending post, a parting plate, a 125 frame for said plate, bearings for rotatably supporting said frame, arms to which the bearings are slidably held to permit vertical movement of the parting frame and plate clamping fingers adapted to engage 130

one of the presser boards, rods to which said fingers are held and means whereby lengthwise movement may be given to the rods to cause the fingers to press upon the presser board of the flask, together with means for pivotally mounting the arms upon the vertical post to permit the frame to be moved between the presser devices or away therefrom.

10 48. The combination with a frame, of relatively movable pressing devices supported by said frame, a parting plate, a frame for said plate, arms to which the bearings are slidingly held to permit vertical movement of the parting plate frame, clamping fingers adapted to engage one of the flask pressing boards, and means for moving the fingers toward or away from the flask.

49. The combination with a supporting frame, of a normally fixed pressing device, a movable pressing device, a valve, means controlled by said valve whereby air under pressure may cause the said movable pressing device to move in either direction, a bar carried by the movable pressing device and having a slotted lower end, a lever held to the stem of the controlling valve, an arm connected to the lever and arranged in the

path of movement of the vertically movable bar, and a screw carried by the bar and adapted to engage the arm to operate the same and shift the lever to shut off the air pressure and thereby stop the movement of the movable pressing device.

50. The combination with a supporting frame, of a pressing device, a movable pressing device, a valve, means controlled by said valve whereby air under pressure may cause the said movable pressing device to move in either direction, a bar carried by the movable pressing device, a lever held to the stem of the controlling valve, an arm connected to the lever and arranged in the path of movement of the vertically movable bar, and means carried by the bar and adapted to engage the arm to operate the same and shift the lever to shut off the air pressure and thereby stop the movement of the movable pressing device.

This specification signed and witnessed 50
this 3rd day of January, A. D. 1911.
